DESIGN FOR A SCARF OR SIMILAR ARTICLE

Andrew W. Roth, New York, N. Y.

Application January 22, 1941, Serial No. 98,288

Term of patent 3½ years

To all whom it may concern:

Be it known that I, Andrew Wm. Roth, a citizen of the United States, residing in New York city, in the county of New York and State of New York, have invented a new, original, and ornamental Design for a Scarf or Similar Article, of which the following is a specification, reference being had to the accompanying drawing, forming part thereof.

The figure is a plan view of a quarter portion of a scarf showing a complete unit of my design.

The design unit is contained between the dot and dash lines and border lines of the outer corner of the scarf, which unit constitutes a quarter portion of the complete scarf, being repeated in regular succession over the entire surface thereof.

I claim:

The ornamental design for a scarf or similar article, substantially as shown and described.

ANDREW W. ROTH.
